UNITED STATES PATENT OFFICE.

CLAUDE E. DORSEY, OF ELBA, ALABAMA.

DOUBLE TAKE-UP FOR CABLES.

Application filed January 29, 1926. Serial No. 84,678.

This invention relates to cable or rope take-ups for tree and stump pulling machines, and has for one of its objects the provision of a novel, simple, durable and highly efficient device of this character that can be readily connected to the main cable or rope of a machine at any point in the length thereof and that shall be provided with an eye to permit one or more branch cables or ropes to be readily connected thereto so as to permit the successive pulling of trees or stumps.

With the above and other objects in view, the invention consists of the novel construction, combination and arrangement of parts hereinafter fully described and claimed, and illustrated in the accompanying drawings, wherein:

Figure 1 is a top plan view illustrating the application of a take-up constructed in accordance with my invention,

Figure 2 is a plan view of the take-up on an enlarged scale,

Figure 3 is a view in edge elevation of the take-up,

Figure 4 is a similar view looking at the take-up from another direction,

Figure 5 is a sectional view taken on the plane indicated by the line 5—5 of Figure 2,

Figure 6 is a sectional view taken on the plane indicated by the line 6—6 of Figure 2, and

Figure 7 is a sectional view taken on the plane indicated by the line 7—7 of Figure 3.

Corresponding and like parts are referred to in the following description, and designated in the several views of the accompanying drawings, by similar reference characters.

The take-up comprises a ring 1 provided in its periphery with a spiral groove 2 for the reception of the main cable or rope 3 of the stump pulling machine. The side walls 4 and 4^a of the groove 2 are extended laterally to provide a front flange 5 and a rear flange 6, and the side wall 4 of the groove is extended laterally to provide a flange 7. The flanges 5 and 6 are located at the ends of the groove 2 and are provided with cable or rope retaining lugs 5^a and 6^a respectively. These flanges are located at one side of the ring 1 and at opposite sides of the groove 2, and the flange 7 is located at that side of the ring 1 nearest the flange 5. The flange 7 is provided with a lug 8

which extends across and has a concentric arrangement with respect to the groove 2, and is provided with an opening 8^a for the reception of one end of a branch cable or rope 9. Said end of the branch cable or rope 9 is provided with a stop 10 to prevent the cable or rope from becoming detached from the lug 8.

The wall 4 of the groove 2 is also extended to provide a flange 11 which has a tangential arrangement with respect to the ring 1 and is located opposite and extends rearwardly beyond the flange 6. The flange 11 is provided rearwardly beyond the flange 6 with an opening 11^a, and constitutes an eye for the reception of a hook 12 to which a plurality of branch cables or ropes 13 are secured. The flanges 5, 6 and 11, together with the adjacent portions of the ring 1, are provided with reinforcing or strengthening ribs 14. The branch cables or ropes 9 and 13 are provided with hooks 9^a and 13^a respectively to permit them to be secured about the trees or stumps to be pulled, and one or more take-ups can be applied to the main cable or rope 3.

From the foregoing description, taken in connection with the accompanying drawings, it will be readily apparent that the take-up can be readily attached to the main cable or rope 3 at any point in the length thereof, that the take-up is permanently provided with a branch cable or rope 9, and that the branch cables or ropes 13 are detachably connected to the take-up. The device permits one, two, three or more trees or stumps to be successively pulled. The hook 12 may be provided with one, three or more branch cables or ropes, and as the device is provided with one permanent branch cable or rope and may be provided with one or more detachable branch cables or ropes it may properly be termed a double take-up assembly.

It should be understood that the drawings are merely illustrative and do not pretend to give exact proportions. Furthermore, the said drawings are illustrative of a preferred construction, it being my expectation that various changes and modifications may be made without departing from the spirit and scope of my invention.

What is claimed is:—

1. A take-up of the character set forth, comprising a ring provided in its periphery with a spiral groove, flanges extending laterally from one side of the ring at the ends

- of the groove and located at opposite sides of the groove and provided with cable or rope retaining lugs, a flange extending from the ring opposite one of said first named flanges and provided with an opening so as to constitute an eye, an element detachably engaged with the eye, and a branch cable or rope connected to the element and provided with a hook.
- 10 2. A take-up of the character set forth, comprising a ring provided in its periphery with a groove for the reception of the main cable or rope, front and rear cable or rope retaining elements extending from the ring, and an eye extending from the ring and lo-

cated opposite the rear rope retaining element.

3. A take-up of the character set forth, comprising a ring provided in its periphery with a groove, front and rear retaining elements extending laterally from one side of the ring and located at opposite sides of the groove, and a flange extending laterally from the ring and located opposite and extending rearwardly beyond said rear retaining element, and said flange being provided beyond said rear retaining element with an opening.

In testimony whereof I affix my signature.

CLAUDE E. DORSEY.
